CABLE STRIPPING TOOL

Gordon K. Hurlbut, Chenango Bridge, N.Y., assignor to
Gagne Associates, Inc., Binghamton, N.Y., a corpora-
tion of New York

Filed Feb. 26, 1963, Ser. No. 73,724

Term of patent 14 years

(Cl. D54—13)

FIG. 1

FIG. 2

FIG. 3

FIGURE 1 is a left side elevational view of a cable stripping tool, showing my new design;

FIGURE 2 is a right side elevational view thereof; and
FIGURE 3 is a front elevational view thereof.

I claim:

The ornamental design for a cable stripping tool, sub-
stantially as shown.
